US00D875587S

(12) **United States Design Patent** (10) **Patent No.:** **US D875,587 S**
(45) **Date of Patent:** **** Feb. 18, 2020**

(54) **WEARABLE DEVICE**

- (71) Applicant: **Apple Inc.**, Cupertino, CA (US)
- (72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)
- (73) Assignee: **Apple Inc.**, Cupertino, CA (US)
- (**) Term: **15 Years**
- (21) Appl. No.: **29/683,146**
- (22) Filed: **Mar. 11, 2019**

Related U.S. Application Data

- (63) Continuation of application No. 29/646,731, filed on May 7, 2018, now Pat. No. Des. 842,740, which is a continuation of application No. 29/601,146, filed on Apr. 19, 2017, now Pat. No. Des. 817,203, which is a continuation of application No. 29/565,456, filed on

May 20, 2016, now Pat. No. Des. 784,831, which is a continuation of application No. 29/519,695, filed on Mar. 6, 2015, now Pat. No. Des. 756,825, which is a continuation of application No. 29/499,091, filed on Aug. 11, 2014, now Pat. No. Des. 737,158, said application No. 29/565,456 is a continuation of application No. 29/519,679, filed on Mar. 6, 2015, now Pat. No. Des. 756,824, which is a continuation of application No. 29/499,042, filed on Aug. 11, 2014, now Pat. No. Des. 728,624, and a continuation of application No. 29/499,091, filed on Aug. 11, 2014, now Pat. No. Des. 737,158, and a continuation of application No. 29/499,084, filed on Aug. 11, 2014, now Pat.
